DESIGN FOR A COMBINED SHIPPING AND DISPLAY CONTAINER

Betty Vivian Dubiner, Toronto, Ontario, Canada

Application April 9, 1945, Serial No. 118,926
In Canada December 2, 1944

Term of patent 14 years

(Cl. D80—5)

To all whom it may concern:

Be it known that I, Betty Vivian Dubiner, a British subject, residing at the city of Toronto, in the county of York, Province of Ontario, Dominion of Canada, have invented a new, original, and ornamental Design for a Combined Shipping and Display Container, of which the following is a specification, reference being had to the accompanying drawing forming part thereof.

Figure 1 is a perspective view of the combined

shipping and display container, showing my new design; and

Figure 2 is an end elevation of the container.

The interior of the right end of the container is the same as that shown through the open door on the left centre.

I claim:

The ornamental design for a combined shipping and display container, as shown and described.

BETTY VIVIAN DUBINER.
